VENTILATION SYSTEM FOR BOATS

John S. Fluor, Jr., Anaheim, Calif., assignor to
 The Fluor Corporation, Ltd., Los Angeles, Calif.,
 a corporation of California

Application July 19, 1943, Serial No. 495,301

14 Claims. (Cl. 114—211)

The primary object of this invention is to provide improved ventilating systems for compartments or rooms in boats equipped with internal combustion engines either as prime movers for driving the boats, or for operating auxiliary equipment such as generators, pumps, and the like. More particularly, the invention is directed to improved boat ventilating systems whereby the displacement of air for creating the ventilating air circulation, is accomplished by virtue of the exhaust gas discharge from one or more of the engines.

A co-pending application Serial No. 495,300 filed by Peter E. Fluor on Ventilation and exhaust pipe cooling in boats, discloses an improved system for ventilating boat compartments containing internal combustion engines, by utilizing the exhaust gas flow from the engine both to draw cool fresh air into the atmosphere of the compartment and to remove air warmed by heat from the engine. The present invention is concerned with the ventilation of compartments in the ship other than the engine-containing compartment, although it is contemplated that the ventilating system as a whole shall ordinarily include provision for ventilating the engine room.

In carrying out the invention, the engine exhaust gases are discharged into a warm air conduit to induce air flow therethrough, as by jacketing the exhaust pipe with the conduit throughout the entirety or a portion of the exhaust pipe length, as later described. Ordinarily the conduit will be extended into the engine compartment and provided with a warm air inlet located to induce cool air circulation within the atmosphere of the engine compartment. Provision is made for ventilating other compartments separate from the engine compartment by extending from the conduit surrounding the exhaust pipe, one or more branch conduits, as the occasion may require, leading to such other compartments to be ventilated. Individually the compartments are supplied with cool air through a suitable arrangement of inlet ducts. For the purposes of the invention, induction of warm air through the branch conduits is accomplished in a manner establishing effective air circulation within the ventilated compartments, by placing the conduit inlets at locations distant from the locations of cool air entry, and, if desired, by providing control valves for regulating the rate of air flow through either or both the inlet ducts and the warm air outlets.

A further feature of the invention is the provision of a pressure responsive valve for prevent-

ing any back flow of combustion gases through the conduit branch into the ventilated compartment. For this purpose, I employ a suitable type of valve which opens to permit normal air flow from the compartment under the influence of the induced draft, and closes, in the event for any reason of reverse flow, to preclude the possibility of noxious gases entering the compartment.

The invention has various additional particular objects and details, but these will be understood without necessity for further preliminary description, by reference to the accompanying drawing illustrative of the invention in a typical embodiment. In the drawing:

Fig. 1 is a diagrammatic sectional view showing the ventilating system incorporated in a conventionally illustrated arrangement of separate compartments in a boat; and

Fig. 2 is a fragmentary enlarged sectional view of the pressure responsive air valve.

For purposes of description, assume that the system is to be used for the ventilation of separate compartments located at the same or different levels below the main deck 10 of the boat. As illustrative, I have shown compartments 11 and 12 at a lower level, and compartments 13 and 14 above. Compartment 15 contains an internal combustion engine, conventionally indicated at 16, driving a generator 17, or serving as a power source for any other purpose. Access is had to the engine compartment 16 through a vertical trunk or duct 18 extending to the atmosphere above the deck 10. The exhaust pipe extends from the engine upwardly through the duct 18 to connect with muffler 20 above the deck.

The exhaust pipe 19 is jacketed by a conduit 21 including a stack 22 surrounding and extending above the muffler 20 and within which the muffler is supported, the conduit 21 preferably being extended downwardly into the engine compartment 15, and to the engine itself, to permit constant withdrawal of heat from the exhaust pipe throughout its length. The discharge of exhaust gases from the muffler into the passage within the stack throat at 22a induces air flow upwardly through the conduit 21 at a rate sufficient for effective ventilation not only of the engine compartment 15, but other separate compartments as well. In general, selectively controlled ventilation of the several compartments is accomplished by connecting with the main conduit 21, one or more branch conduits, the particular location and extent of which may be

made to suit the requirements of particular installations.

As illustrative, branch conduit 23 is shown to extend within the engine compartment 15 and to be provided with an inlet 24 which, as in the case of the other branch conduits, may be controlled by a suitable damper or valve 25. Induction of air through the inlet 24 creates a downward flow of fresh air through the duct 18 into the compartment, and thereafter a cross circulation past the engine in rising to the outlet. If desired, further provision may be made for removing the warm air more directly from the engine, as by branch conduit 26 extending above it.

Fresh air may be supplied to the compartments 16 to 13 by any suitable arrangement of separate or interconnected ducts, as for example pipes 27 and 28 extending from above the deck 10 to the valve controlled outlets 27a and 28a in the compartments as illustrated. Warm air may be withdrawn from compartment 11 through an extension 23a of the conduit branch 23. The withdrawal of warm air from compartments 12, 13, and 14 may occur through one or more separate branch conduits, as for example conduit 29 having air inlets at 30, 31, and 32.

As previously mentioned, provision may be made for precluding the possibility of exhaust gases entering the compartment from the conduit 21. For this purpose, safety check valves 33 may be installed at suitable locations in the branch conduits 23, 26 and 29. While any suitable type and form of check valve may be used for this purpose, I have shown in Fig. 2 the valve assembly 33 to comprise a body 34 containing a flapper disc valve 35 pivotally supported at 36 and engageable with an annular seat 37. The normal induced flow of air in the direction of the arrow opens the valve to permit free air passage to the outlet conduit. Any back flow of air or gas, however, seats the valve to close the conduit branches against back flow of the gas.

As actually installed, the system may include various additional details such as the provision of gate valves or the like for closing the various ducts and conduit branches against the flow of water therethrough under emergency conditions. Such details, however, are incidental to the invention and need not be shown or further described.

I claim:

1. In a boat having below its deck a compartment containing an internal combustion engine, an exhaust pipe extending from the engine, and a second separate compartment; a ventilating system comprising a conduit leading from said second compartment, and means creating a flow of air from said second compartment through the conduit by virtue of the exhaust gas discharge through said pipe.

2. In a boat having below its deck a compartment containing an internal combustion engine, an exhaust pipe extending from the engine, and a second separate compartment; a ventilating system comprising a conduit leading from said second compartment and surrounding a considerable length of the exhaust pipe, and means creating a flow of air from said second compartment through the conduit and along the exhaust pipe by virtue of the exhaust gas discharge through said pipe.

3. In a boat having below its deck a compartment containing an internal combustion engine, an exhaust pipe extending from the engine, and

a second separate compartment; a ventilating system comprising conduit means leading from both of said compartments, and means creating air flow from said compartments through the conduit means by virtue of the exhaust gas discharge through said pipe.

4. In a boat having below its deck a compartment containing an internal combustion engine, an exhaust pipe extending from the engine, and a second separate compartment; a ventilating system comprising conduit means leading from both of said compartments, means creating air flow from said compartments through the conduit means by virtue of the exhaust gas discharge through said pipe, and means for selectively controlling such air flow from the compartments.

5. In a boat having below its deck a compartment containing an internal combustion engine, an exhaust pipe extending from the engine, and a second separate compartment; a ventilating system comprising a conduit extending from said engine-containing compartment in spaced relation about the exhaust pipe, a branch extending from said conduit to said second compartment, and means creating a flow of air from said second compartment through the branch conduit and along the exhaust pipe by virtue of the exhaust gas discharge through said pipe.

6. In a boat having below its deck a compartment containing an internal combustion engine, an exhaust pipe extending from the engine, and a second separate compartment; a ventilating system comprising a conduit leading from said second compartment, a duct for supplying fresh air to said second compartment, and means creating a flow of air through said duct into the second compartment atmosphere and a flow of air therefrom through said conduit, by virtue of the engine exhaust gas discharge through said pipe.

7. In a boat having below its deck a compartment containing an internal combustion engine, an exhaust pipe extending from the engine, and a second separate compartment; a ventilating system comprising a conduit leading from said second compartment, a duct for supplying fresh air to said second compartment, and means creating a flow of air through said duct into the second compartment atmosphere and a flow of air therefrom through said conduit from a location in the compartment distant from the location of fresh air entry thereto through said duct, by virtue of the engine exhaust gas discharge through said pipe.

8. In a boat having below its deck a compartment containing an internal combustion engine, an exhaust pipe extending from the engine, and a second separate compartment; a ventilating system comprising conduit means leading from both of said compartments, ducts for supplying fresh air to said compartments, and means creating a flow of air through said ducts into the compartment atmospheres and withdrawal of warm air therefrom through said conduit means, by virtue of the engine exhaust gas discharge through said pipe.

9. In a boat containing an internal combustion engine, a plurality of separate compartments below the boat deck, and fresh air ducts leading to said compartments; the combination comprising conduits leading from said compartments, and means creating fresh air flow through said ducts into the atmospheres of said compartments and air flow therefrom through said con-

duits, by virtue of the exhaust gas discharge from said engine.

10. In a boat containing an internal combustion engine, a plurality of separate compartments below the boat deck, and fresh air ducts leading to said compartments; the combination comprising conduits leading from said compartments, means creating fresh air flow through said ducts into the atmospheres of said compartments and air flow therefrom through said conduits, by virtue of the exhaust gas discharge from said engine, and means for selectively controlling the withdrawal through said conduits of air from the compartments.

11. In a boat containing below its deck an internal combustion engine, an exhaust pipe extending from the engine to the deck, a plurality of separate compartments below said deck, and fresh air ducts leading to said compartments; the combination comprising a conduit surrounding said exhaust pipe, branches leading from said conduit to said compartments, and means creating fresh air flow through said ducts into the atmospheres of said compartments and air flow therefrom through said branches and conduit along the exhaust pipe, by virtue of the exhaust gas discharge from said pipe.

12. In a boat containing an internal combustion engine, and a compartment below the boat deck; a ventilating system comprising a conduit leading from said compartment, means for cre-

15 5 ating a flow of air from the compartment atmosphere through said conduit by virtue of the exhaust gas discharge into a passage communicating with said conduit, and means preventing flow of exhaust gas through said conduit into the compartment.

10 13. In a boat containing an internal combustion engine, and a compartment below the boat deck; a ventilating system comprising a conduit leading from said compartment, means for creating a flow of air from the compartment atmosphere through said conduit by virtue of the exhaust gas discharge into a passage communicating with said conduit, and a pressure responsive check valve in said conduit for preventing flow of exhaust gas therethrough into the compartment.

15 20 25 14. In a boat containing an internal combustion engine, an exhaust pipe extending from the engine, and a compartment below the boat deck; a ventilating system comprising a conduit surrounding and extending along the exhaust pipe, a branch connecting said conduit with said compartment, means for creating a flow of air from the compartment atmosphere through said branch and conduit by virtue of the exhaust gas discharge, and pressure responsive valve means in said branch for preventing flow of exhaust gas through said conduit into the compartment.
